CLAIM

The ornamental design for a card and gift box, as shown and described.

DESCRIPTION

FIG. 1 is a perspective top, front, right view looking down towards the top;

FIG. 2 is a rear view thereof, the front being a mirror image;

FIG. 3 is a left side view thereof;

FIG. 4 is a bottom view thereof; and,

FIG. 5 is a perspective view thereof; shown in an open condition; the broken line showing the contents is for illustrative purpose only and forms no part of the claimed design.
